Application February 1, 1946, Serial No. 644,918

8 Claims. (Cl. 74—27)

1

This invention relates to operating mechanism for printing presses and the like. It relates particularly to operating mechanism for a printing press or the like having an oscillating element such as a bed. The invention provides means for driving the oscillating element; when it is employed for driving the bed of a printing press it takes the form of what is known in the art as a "bed motion." The invention is especially adapted and intended for use in printing presses of the flat bed and cylinder type, although it may be adapted for numerous other uses.

The invention will be described as embodied in a flat bed and cylinder press. Bed motions for such presses have employed parts, such as hangers, of considerable weight carried by the bed and whose momentum has had to be overcome when the bed is stopped and reversed at each end of the stroke; also the bed driving mechanism has had a tendency to skew the bed. Both of these factors are greatly magnified in presses operated at high speed and impose upon the working parts very high stresses. They also tend toward imperfection in printing unless counteracted by additional and expensive means. As a result it has been necessary to provide especially strong and massive driving, operating and supporting mechanism to insure proper operation of the press at the desired speed despite the great mass of moving parts and to effectively counteract the tendency of the bed to skew. This in turn has undesirably increased the cost and size of presses as well as the expense of operation due to power consumption and cost of replacement parts.

I provide a simple and efficient bed motion well adapted for high speed operation in which the mass of the bed and associated mechanism is greatly reduced and the bed driving mechanism acts on the bed in such a way as to avoid any substantial tendency toward skewing. I eliminate entirely the use of bed hangers and provide bed driving means of comparatively very light weight, greatly reducing the dead weight of the bed and making possible high speed operation employing a minimum of power. I may use a substantially smaller motor than would otherwise be necessary, and in general the press may be more lightly designed, resulting in an important saving in first cost and cost of upkeep and operation.

I preferably provide separate means for driving the bed during constant speed motion and for reversing the bed at the ends of its stroke. I provide for driving the bed during constant speed motion by applying the driving force to

2

the bed in such a way as to avoid any substantial tendency to skew the bed. Desirably I provide an elongated operating member adapted to be carried by the bed to lie generally in a longitudinal plane perpendicular thereto and containing the center of gravity thereof and means coacting with said member to drive the bed in both directions of oscillation. The elongated operating member may conveniently take the form of a rack, and the means coacting therewith may conveniently take the form of pinion means. For example, I may employ two pinions rotating in opposite directions, and bring such pinions alternately into mesh with the rack to drive the bed during constant speed motion. The pinions may be geared together in such manner that when one of them turns in either direction the other turns in the opposite direction. Means may be provided for shifting the pinions transversely of the rack to bring first one and then the other into mesh with the rack.

Desirably the pinions for driving the bed during constant speed motion are out of mesh with the rack at the ends of the stroke of the bed when it is being reversed. This may be accomplished by providing the rack of such length that its trailing end passes out of mesh with the pinion which has been driving it during constant speed motion of the bed before or at approximately the instant when the bed begins to slow down for reversal.

As above indicated reversing of the bed is desirably accomplished by means separate from the means above referred to for driving the bed during constant speed motion. I preferably provide an elongated operating member adapted to be carried by the bed and means coacting with such elongated operating member for slowing down, stopping and reversing the bed at at least one end of its oscillatory movement. The elongated operating member may conveniently take the form of a rack and the means coacting therewith may take the form of a pinion meshing therewith after the rack through which the bed is driven in constant speed motion has passed beyond the driving pinions coacting therewith. I find it desirable to render operative the bed reversing means at approximately the same time as the means for driving the bed in constant speed motion are rendered inoperative. The two means may both be operative simultaneously during a very short portion of the movement of the bed to insure control of the bed at all times and proper transition of the operation of the bed from the one means to the other and vice versa.

I preferably employ similar bed reversing mechanisms for reversing the bed at the respective ends of its stroke.

Reversal of the bed is preferably accomplished by oscillatory means moving at first in synchronism with the bed at the end of its constant speed motion, the oscillatory means being slowed to a stop and then moved back in the opposite direction to reverse the bed. The oscillatory means may take the form of a crosshead operated by a crank, the crosshead carrying a rack meshing with a gear or segment which in turn is connected, directly or through intermediate gearing, with the pinion meshing with the rack on the bed which is used for bed reversal. I find it convenient to employ a single oscillatory member consisting of a crosshead operated by a crank, the crosshead carrying two racks respectively connected through gearing to act on the pinions which mesh with the racks connected with the bed for effecting reversal of the bed at the respective ends of its stroke.

Other details, objects and advantages of the invention will become apparent as the following description of a present preferred embodiment thereof proceeds.

In the accompanying drawings I have shown a preferred embodiment of the invention, in which

Figure 1 is a vertical transverse cross-sectional view through a portion of a printing press showing the bed motion;

Figure 2 is a plan view of the bed motion; and

Figures 3 to 10, inclusive, are diagrams showing the positions of certain of the parts at various stages during the press cycle, as follows:

Figure 3 shows the bed at the end of its constant speed motion toward the left on the return or non-printing stroke, the bed being ready to slow down;

Figure 4 shows the bed stopped at the end of the return stroke ready to move toward the right on the impression or printing stroke;

Figure 5 shows the bed moving toward the right on the impression stroke and at the beginning of constant speed motion;

Figure 6 shows the bed in the middle of constant speed motion moving toward the right on the impression stroke;

Figure 7 shows the bed at the end of its constant speed motion toward the right on the impression stroke and ready to slow down;

Figure 8 shows the bed in its extreme right hand position at the end of the impression stroke and ready to move back toward the left on the return stroke;

Figure 9 shows the bed at the beginning of constant speed motion on the return stroke;

Figure 10 shows the bed in the middle of constant speed motion on the return stroke.

Referring now more particularly to the drawings, there is shown at 2 the impression cylinder of a flat bed and cylinder press and at 3 the bed of the press. The press may operate in conventional manner, the cylinder rotating continuously in the same direction (counterclockwise in Figures 3-10) and making two complete revolutions for each cycle of the bed; that is, the cylinder rotates once while the bed is moving forward on the impression or printing stroke and once while it is moving back on the return stroke. When the bed moves forward on the impression stroke the cylinder cooperates with the bed in printing. On the return stroke of the bed the cylinder while continuously rotating in the forward direction is raised relatively to the bed so that it does not

contact the bed, as shown, for example, in Figures 9 and 10. This is the standard method of operation of flat bed and cylinder presses and the mechanism for raising and lowering the impression cylinder during operation is well known.

Connected with the cylinder 2 coaxially therewith and having a pitch diameter equal to the diameter of the cylinder is a cylinder driving gear 4. The cylinder driving gear 4 meshes with an idler pinion 5 rotatably carried on a stub shaft 6 mounted in the press frame 7. Journaled for rotation in the press frame is a shaft 8 to which is keyed a gear 9 meshing with the pinion 5. Also keyed to the shaft 8 is a gear 10.

15 Journaled for rotation in the press frame is a shaft 11 to which is keyed a flywheel 12. Also keyed to the shaft 11 is a pulley 13. The press is driven by an electric motor (not shown) which drives a pulley 14. A series of V belts 15 are 20 trained about the pulley 13 and 14. Thus when the motor is operated it rotates the pulley 14 which through the belts 15 causes rotation of the pulley 13. This turns the flywheel shaft 11.

Keyed to the flywheel shaft 11 is a pinion 16 25 which meshes with the gear 10 keyed to the shaft 8. Thus the motor through the shaft 11 drives the shaft 8 continuously in the same direction; and the shaft 8 through the gear 9, the pinion 5 and the gear 4 rotates the impression cylinder 2 30 continuously in the same direction.

Mounted in the press frame for rotation and also for axial movement is a shaft 17. Pinned to the shaft 17 are two spaced apart collars 18. Mounted on the frame is a bracket 19 to which is 35 pivoted at 20 a lever 21 whose upper end is bifurcated and carries opposed rollers 22 positioned between the collars 18 and of such diameter as to simultaneously engage said collars, as shown in Figures 1 and 2. The lower end of the 40 lever 21 carries a cam follower roller 23 which operates in a cam groove 24 of a rotary cam 25 keyed to a shaft 26 rotatably mounted in the press frame. Also keyed to the shaft 26 is a gear 27 which meshes with a pinion 28 pinned to 45 the shaft 8. Thus upon rotation of the shaft 8 the cam 25 is caused to rotate continuously, and that cam through the cam groove 24 and the cam follower roller 23 causes the lever 21 to oscillate about the axis of its pivotal connection 20 with the bracket 19. But as the rollers 22 carried by the lever 21 are positioned between and in 50 contact with the collars 18 which are pinned to the shaft 17 the angular oscillation of the lever 21 causes axial oscillation of the shaft 17. The 55 cam groove 24 is designed to oscillate the shaft 17 from one extreme position to the other when the bed is adjacent each end of its stroke, that is, after conclusion of the constant speed motion of the bed in each direction. During the constant speed motion of the bed the cam follower roller 23 dwells in a circular portion of the cam groove 24 to hold the shaft 17 in one or the other of its extreme axial positions. The reason for 60 axial shifting of the shaft 17 will presently appear.

Mounted on the shaft 17 is a pinion 29 which is always in mesh with the gear 10 regardless of the axial position of the shaft 17. To insure that 65 the pinion 29 will always remain in mesh with the gear 10 the former is made with a wide face as shown in Figures 1 and 2. I prefer to pin the pinion 29 to the shaft 17 as shown at 30 in Figure 1 so as to cause the shaft 17 to rotate during 70 operation of the press. While it is not necessary

that the shaft 17 rotate this is desirable because of its endwise movement. If the shaft is turning it will move endwise in its bearings much more freely than if it were non-rotative.

Positioned on the shaft 17 adjacent the pinion 29 is a pinion 31 which is of the same diameter as the pinion 29. The pinion 31 is designed to rotate relatively to the shaft 17, wherefore a bushing 32 is interposed between the pinion 31 and the shaft. A collar 33 is pinned to the shaft 17 and maintains the pinion 31 and the bushing 32 in place on the shaft 17 in fixed axial position relatively to the pinion 29. Between the pinions 29 and 31 is a frame or spider 34 (Figures 1, 2 and 3) having three radial shafts 35 equally spaced angularly about the frame or spider with a bevel pinion 36 mounted on each shaft 35. Fastened to the pinion 29 by screws 37 is a bevel gear 38. Fastened to the pinion 31 by screws 39 is a bevel gear 40 of the same size as the bevel gear 38. The bevel gears 38 and 40 mesh with the bevel pinions 36 of the spider 34.

The spider 34 has a projection 41 extending out between the pinions 29 and 31 which projection has its end bifurcated as shown at 42 in Figure 3 to embrace a rod 44 mounted in the press frame. This prevents the spider from turning about the axis of the shaft 17. The spider is likewise maintained in fixed position axially of the shaft 17 so that it partakes of the axial movements of that shaft along with the pinions 29 and 31. When the shaft 17 moves axially the bifurcated end 42 of the projection 41 slides along the rod 44.

Since the spider 34 is held against turning, and since the bevel pinions 36 mesh with the bevel gear 38 carried by the pinion 29 and also with the bevel gear 40 carried by the pinion 31, the pinions 29 and 31 will always be caused, when one of them is driven, to rotate in opposite directions at the same speed. The pinion 29, being pinned to the shaft 17, has no movement relatively to the shaft, but the pinion 31 rotates in the direction opposite the direction of rotation of the shaft, the relative rotational speed of the pinion 31 and the shaft being double the rotational speed of the shaft.

Fastened to the under face of the bed 3 is an elongated operating member in the form of a downwardly facing rack 45. The rack 45 extends parallel to the length of the bed and parallel to the direction of oscillation of the bed. It is preferably disposed to lie generally in a longitudinal plane perpendicular to the bed and containing the center of gravity thereof. If the bed is transversely symmetrical the rack 45 is preferably disposed at the longitudinal center line thereof. The reason for thus disposing the rack 45 is to avoid any substantial tendency toward skewing of the bed when it is driven during constant speed motion, especially on the impression stroke. The rack 45 is adapted to mesh alternately with the respective pinions 29 and 31 during constant speed motion of the bed in its respective directions of oscillation, the length of the rack being such that substantially at the end of the constant speed motion of the bed in each direction its trailing end will pass beyond and hence out of mesh with that one of the pinions 29 and 31 with which it was last in mesh. While the rack 45 is out of mesh with the pinions 29 and 31 other mechanism, presently to be described, effects reversal of the bed. When the bed next reaches the point at which it is to commence its constant speed motion the leading end of the rack 45 comes into mesh with the one of the

pinions 29 and 31 which is to mesh with it during such constant speed motion.

The function of the pinions 29 and 31 is to drive the bed during constant speed motion. One of those pinions drives the bed in one direction of oscillation and the other drives it in the opposite direction of oscillation. When the pinion 29 is in mesh with the rack 45, as shown in Figure 1, that pinion drives the bed during constant speed motion in one direction. After the trailing end of the rack 45 has passed out of mesh with the pinion 29 the cam 25 shifts the shaft 17 axially toward the left, viewing Figure 1, to move the pinion 29 laterally out of the path of the rack 45 and the pinion 31 into such path. While this shifting is taking place the bed is being reversed, and when it reaches the stages on the next oscillatory movement when it is ready to begin its constant speed motion the forward end of the rack enters into mesh with the pinion 31, which pinion through the rack 45 drives the bed during constant speed motion in that direction. The shaft 17 always turns in the clockwise direction when one looks at it axially from its left hand end viewing Figure 1 so the pinion 29 drives the bed toward the viewer in Figure 1 or toward the right viewing Figures 5, 6 and 7, while the pinion 31 drives the bed away from the viewer in Figure 1 or toward the left viewing Figures 3, 9 and 10. The linear speed of the pinions 29 and 31 at the pitch lines thereof is equal to the speed of the bed during constant speed motion. When the bed nears the end of its stroke and the rack 45 passes out of mesh with the pinion 29 or 31 which has been driving it the bed is slowed up, stopped and reversed, and by the time the leading end of the rack 45 comes into mesh with the pinion 29 or the pinion 31 on the succeeding oscillatory movement of the bed the speed of the bed will have been brought up to approximately the speed of its constant speed movement, whereupon control of the bed is again taken over by the mechanism which has been described.

The mechanism for reversing the bed at the ends of its stroke will now be described. The shaft 17 rotates in bushings 46 which are disposed in bearings in the frame and two of which bushings extend axially within the hubs of pinions 47 and 48 which are rotatable thereon (Figure 1). The hub of the pinion 47 is provided with an annular groove 49 receiving a projection 50 of a member 51 bolted to the frame by a bolt 52, whereby to hold the pinion 47 against movement relatively to the frame axially of the shaft 17. Similarly the pinion 48 is held against movement relatively to the frame axially of the shaft 17 by a plate 53 fastened by a screw 54 to the frame and entering an annular groove 55 in the hub of the pinion 48.

The pinion 47 meshes with a segment 56 rotatable upon a bushing 57 disposed about the shaft 8, which segment 56 is integral with a segment 58 of smaller diameter and disposed opposite the segment 56. The pinion 48 meshes with a segment 59 rotatable upon a bushing 60 disposed about the shaft 8, which segment 59 has connected therewith by screws 61 a segment 62 of a diameter equal to the diameter of the segment 58 and facing in the same direction as the segment 59.

Fastened to the under side of the bed 3 are two relatively short longitudinally extending racks 63 and 64. The racks 63, 64 and 45 are all parallel to one another, the rack 63 being disposed adjacent one end of the rack 45 and over-

lapping it slightly (about three teeth) and the rack 64 being disposed adjacent the other end of the rack 45 and overlapping it to about the same extent. The pinion 47 is adapted to mesh with the rack 63 when the bed is at and adjacent one end of its movement, and the pinion 48 is adapted to mesh with the rack 64 when the bed is at and adjacent the other end of its movement. The function of the pinions 47 and 48 is to reverse the bed, one of them reversing it each time it is at one end of its stroke and the other reversing at each time it is at the other end of its stroke. As the bed moves in each direction and passes the point at which the trailing end of the rack 45 leaves the one of the pinions 29 and 31 which has been driving it during its constant speed movement on that stroke one of the racks 63 and 64 is in mesh with its corresponding reversing pinion. The reversing pinion slows to a stop and then turns in the opposite direction, causing reversal of the bed. The reversing pinion controls the bed until one of the constant speed pinions 29 or 31 takes charge, at which time the reversing pinion passes out of mesh with the short rack with which it cooperates in effecting reversal of the bed.

To accomplish their functions the pinions 47 and 48 must partake of angular oscillation. The means for imparting such oscillation to these pinions will now be described. Mounted in the frame is a shaft 65 carrying a gear 66 which is always in mesh with the gear 10. Integral with the gear 66 and projecting laterally from a face thereof eccentrically thereof is a pin 67. When the gear 66 rotates the pin 67 thus partakes of crank motion. Mounted for rectilinear movement in the frame is a slide 68 comprising a crosshead 69 having therein a vertical slot 70 in which the crank pin 67 operates. The crank pin 67 carries a slide block 71 which as the gear 66 rotates slides up and down in the slot 70 of the crosshead 69. The slide 68 has a guide rod 72 which is received by a guide 73 carried by the frame. The slide also carries two racks 74 and 75, the former facing upwardly and meshing with the segment 58 and the latter facing downwardly and meshing with the segment 62. The slide also has supporting and guiding portions 76 for slidably supporting it on the shaft 8.

As the gear 66 rotates the crank pin 67 and the slide block 71 partake of crank motion and cause the crosshead 69 to move back and forth with simple harmonic motion. Since the rack 74 is always in mesh with the segment 58 and the rack 75 is always in mesh with the segment 62, these segments and also the segments 56 and 59 are constantly being angularly oscillated, and since the latter mentioned segments are always in mesh with the pinions 47 and 48 these pinions likewise constantly partake of angular oscillation. As indicated above the timing is such that each reversing pinion takes control of the bed at the end of constant speed movement of the bed in one direction, brings the bed to a stop and moves it back in the opposite direction until it attains approximately the speed of its constant speed movement, whereupon the means for driving the bed in constant speed movement take control.

A complete cycle of movement of the bed is illustrated in Figures 3 to 10, inclusive, which show the relation of the parts at various stages throughout the cycle.

The bed carries plates 77 which ride upon roller 78 which in turn are mounted in tracks 79 carried

by the press frame whereby the bed is mounted for antifriction movement. It is guided in its oscillatory movement by opposed guides 80 cooperating with portion of the press frame.

By the mechanism described the operation of the bed is effected and controlled in a remarkably advantageous manner, eliminating entirely the heavy hangers and cooperating parts heretofore customarily employed and which have necessitated massive design of the entire press, especially when it is intended for high speed operation. My bed motion provides for relatively light design of a press for given duty and given speed, resulting in a very large saving in first cost, cost of operation and cost of replacement parts as well as an important saving in space requirements.

While I have shown and described a present preferred embodiment of the invention, it is to be distinctly understood that the invention is not limited thereto but may be otherwise variously embodied within the scope of the following claims.

I claim:

1. Operating mechanism for a printing press or the like having an oscillating element such as a bed comprising a rack adapted to be carried by the oscillating element, a driving gear continuously rotatable in one direction, a first pinion continuously in mesh with the driving gear and also adapted to mesh with the rack to drive the oscillating element in one direction of oscillation, a second pinion, connections between the two pinions independent of the driving gear whereby the second is driven from the first but to rotate in the opposite direction and means for relatively moving the pinions and rack transversely of the rack to bring the second pinion into and the first pinion out of mesh with the rack to drive the oscillating element in the opposite direction of oscillation.

2. Operating mechanism for a printing press or the like having an oscillating element such as a bed comprising an elongated operating member adapted to be carried by the oscillating element, a shaft, a pair of rotatable members mounted on said shaft, each of said rotatable members carrying a bevel gear, a frame mounted on said shaft, the frame carrying a bevel pinion meshing with both of said bevel gears, said rotatable members and said frame being held against axial movement relatively to said shaft, means for rotating one of said rotatable members, means for moving said shaft axially to shift said rotatable members relatively to said elongated operating member to bring said rotatable members alternately into coacting relationship with said elongated operating member and means for holding said frame against rotation whereby said rotatable members will rotate in opposite directions when one of them is rotated and will respectively coat with said elongated operating member to drive the oscillating element in its respective directions of oscillation.

3. Operating mechanism for a printing press or the like having an oscillating element such as a bed comprising an elongated operating member adapted to be carried by the oscillating element, a pair of rotatable members, connections between said rotatable members to cause them when one of them is driven to turn in opposite directions, said rotatable members being adapted selectively to coat with said elongated operating member to drive the oscillating element in its respective directions of oscillation, means for shifting said rotatable members relatively to said elongated

operating member to bring said rotatable members alternatively into coacting relationship with said elongated operating member and a driving member separate from said connections coacting with one of said rotatable members to drive it in all positions thereof.

4. Operating mechanism for a printing press or the like having an oscillating element such as a bed comprising a rack adapted to be carried by the oscillating element, a pair of pinions, connections between said pinions to cause them when one of them is driven to turn in opposite directions, said pinions being adapted selectively to mesh with said rack to drive the oscillating element in its respective directions of oscillation, means for shifting said pinions relatively to said rack to bring said pinions alternately into mesh with said rack and a driving gear separate from said connections at all times meshing with one of said pinions to drive it.

5. Operating mechanism for a printing press or the like having an oscillating element such as a bed comprising an elongated operating member adapted to be carried by the oscillating element, a shaft, oppositely rotatable members mounted on said shaft and adapted selectively to coact with said elongated operating member to drive the oscillating element in its respective directions of oscillation, connections between said oppositely rotatable members through which one thereof drives the other thereof, a pair of spaced collars on said shaft, a lever fulcrumed at a point spaced from said shaft and having a portion disposed between said collars and means for swinging said lever about its fulcrum to move said shaft to bring said oppositely rotatable members alternately into coacting relationship with said elongated operating member.

6. In a device of the character described, the combination with a frame of an oscillatable member on the frame, a shaft, means for rotating the shaft in one direction of rotation, a gear on the shaft and connected therewith so as to rotate therewith when the shaft rotates, another gear on the shaft rotatable relatively to the shaft, means driven by the shaft for rotating the second mentioned gear in the direction of rotation opposite that in which the shaft is rotated and shifting means for rendering the first mentioned gear and the second mentioned gear alternately operative for displacing said oscillatable member.

7. In a device of the character described, the

combination with a frame of an oscillatable member on the frame, a shaft, means for rotating the shaft in one direction of rotation, a gear on the shaft and connected therewith so as to rotate therewith when the shaft rotates, another gear on the shaft rotatable relatively to the shaft, means including gearing driven by the first mentioned gear for rotating the second mentioned gear in the direction of rotation opposite that in which the shaft is rotated, means holding both gears against movement relatively to the shaft in the axial direction and means for shifting the shaft in the axial direction to render the respective gears alternately operative for displacing said oscillatable member, the means for rotating the shaft being arranged so as to be operative throughout the range of axial movement of the shaft.

8. In a device of the character described, the combination with a frame of an oscillatable member on the frame, a shaft, means for rotating the shaft in one direction of rotation, a gear on the shaft and connected therewith so as to rotate therewith when the shaft rotates, another gear on the shaft rotatable relatively to the shaft, means driven by the shaft for rotating the second mentioned gear in the direction of rotation opposite that in which the shaft is rotated, oppositely moving synchronously timed oscillatable means for operatively displacing the oscillatable member at the ends of its stroke, means on the oscillatable member for connection with said oscillatable means when both of said gears are inoperative with respect to the oscillatable member and shifting means for rendering the first mentioned gear and the second mentioned gear alternately operative for displacing the oscillatable member intermediate the ends of its stroke.
